UNITED STATES PATENT OFFICE.

FRANK LA OTIS LATHROP, OF WALLINGFORD, CONNECTICUT, ASSIGNOR TO H. L. JUDD COMPANY, OF WALLINGFORD, CONNECTICUT, A CORPORATION OF NEW YORK.

CURTAIN-ROD SOCKET.

1,003,966.

Specification of Letters Patent. Patented Sept. 19, 1911.

Application filed December 31, 1910. Serial No. 600,226.

To all whom it may concern:

Be it known that I, FRANK LA OTIS LATHROP, a citizen of the United States, residing at Wallingford, New Haven county, State of Connecticut, have invented certain new and useful Improvements in Curtain-Rod Sockets, of which the following is a full, clear, and exact description.

My invention relates to an improved curtain rod socket, the object being to provide a simple, and yet durable construction.

In the drawings, Figure 1 is a perspective view of my improved socket, mounted on a bracket, said view being on a slightly enlarged scale. Fig. 2 is a side elevation of the blank from which the socket is made. Fig. 3 is an end elevation thereof. Fig. 4 is a side elevation of the blank after it has been cut to permit the transforming of its shape. Fig. 5 is an end view of the blank shown in Fig. 4. Fig. 6 is a plan view of the finished socket. Fig. 7 is an end elevation thereof.

The socket is made from a cup-shaped cylindrical blank 1 (see Figs. 2 and 3). This blank is first cut or slotted transversely near the closed end or base, as shown at 2 (see Fig. 4). A longitudinal slit 3 is then made in the blank from the open end back to the slit 2. The slit 2 extends only about half way through the blank so as to leave a substantial portion of the forward part of the blank rigidly connected to the base 4 by a curved or semi-circular bond. The two wings 5—6 formed by the slits 2—3 are then turned up as shown in Fig. 7, and are preferably so shaped as to provide a relatively

contracted throat or rod entrance through which a rod of proper size to fit in the socket must be snapped in the act of assembling the rod with the socket. One or more nibs 7—8 may be provided to contract said rod entrance. The base 4 of the socket is provided with an opening 9 to receive a fastening device to secure the socket in place. In Fig. 1, I have shown the socket as secured to an ordinary bracket 10, which, in turn, may be secured to a window casing or wherever it is desired to locate the rod. The method of fastening the base 4 to the bracket 10 may comprise the usual rivet.

It will be seen that by this improved construction, a broad base 4 of substantial area is provided, which supports the forward part of the socket against strains in all directions, and enables said socket to be readily attached by means of a single central fastening.

What I claim is:

In a curtain rod socket, a circular base, an integral tubular portion, a longitudinal slit in the top side of said tubular portion and a transverse slit therein intersecting the longitudinal slit, that part of the tubular portion adjacent to said slits being turned up to form integral wings and to provide a top entrance passage leading into said tubular portion.

FRANK LA OTIS LATHROP.
